US00D653336S

(12) **United States Design Patent**
Morgan et al.

(10) **Patent No.:** US D653,336 S
(45) **Date of Patent:** ** Jan. 31, 2012

(54) **NEEDLE TIP CAP CONNECTOR**

(75) Inventors: **Darrell P. Morgan**, Sonning Common (GB); **Alex Lee**, New York, NY (US); **Dan Formosa**, Piermont, NY (US); **Steven Vordenberg**, Amherst, NH (US); **Joern Vicari**, Brooklyn, NY (US); **Boris Kontorovich**, Brooklyn, NY (US); **Eric Freitag**, New York, NY (US)
